UNITED STATES PATENT OFFICE.

BENJAMIN THAW, JR., OF PITTSBURGH, PENNSYLVANIA.

INTERNAL-COMBUSTION ENGINE.

1,204,610.

Specification of Letters Patent. Patented Nov. 14, 1916.

Application filed January 16, 1914. Serial No. 312,427.

To all whom it may concern:

Be it known that I, BENJAMIN THAW, Jr., a citizen of the United States, and a resident of Pittsburgh, in the county of Allegheny and State of Pennsylvania, have invented an Improvement in Internal-Combustion Engines, of which the following description, in connection with the accompanying drawings, is a specification, like characters on the drawings representing like parts.

This invention relates to internal combustion engines and has particular reference to the valve actuating means thereof.

In order that the principle of the invention may be readily understood, I have disclosed a single embodiment thereof in the accompanying drawings, wherein—

Figure 1 is a vertical, transverse section taken through the cylinder and piston of a reciprocating, internal combustion engine embodying my invention; Fig. 2, a transverse section taken through the intake and exhaust ports of the cylinder; Fig. 3, a horizontal section taken through a four cylinder internal combustion engine embodying my invention; Fig. 4, a development of the sleeve valve preferably employed by me in the practice of my invention; and Figs. 5 and 6 are diagrammatic illustrations of the form of intake and exhaust ports at regular and variable speeds respectively of the sleeve valve.

Referring more particularly to the drawings, the cylinder is represented at 1, it being preferably cast in a single piece and having a waterjacket 2. If desired it may be cored as indicated at 3, to secure lightness of construction. The said cylinder is provided with any suitable ignition means, such as a spark plug 4.

Within the cylinder is positioned the piston 5 having therein a wrist pin 6 to which is connected a piston rod 7, the opposite end of which is pivotally connected in any suitable manner to a crank arm 8, whereby rotative movement imparted to the crank arm 8 reciprocates the piston in the cylinder.

The cylinder is provided with an intake port 9 which is desirably two-thirds the length of the piston stroke, and with an exhaust port 10 which is of the full length of said stroke. Desirably, also, the width

of the intake port and also the exhaust port 5 is sixty degrees, or one-sixth of the circumference of the cylinder.

In accordance with my invention I provide a sleeve valve which is mounted for relative turning movement with respect to the cylinder. Preferably turning movement is imparted to the sleeve valve, and preferably also said sleeve valve is mounted exteriorly of the body of the cylinder. To that end, I have herein represented a cylindrical sleeve 11, which at its lower end is supported upon an annular flange 12 of the cylinder 1, ball bearings 13 being interposed therebetween if desired. Exteriorly of said sleeve I position a cylinder sleeve 14 which at its upper end contacts with the cylinder 1 and is herein represented as secured thereto by bolts 15. Preferably the said sleeve 14 is made in a single part and is slipped onto the cylinder 1 over the upper end thereof. I have herein represented the said sleeve 14 as having a shoulder portion 16 between which and the upper edge of the sleeve valve 7 I may provide ball bearings 17.

As indicated in dotted lines at 18 in Fig. 1, and in full lines in Fig. 4, the sleeve valve 11 is provided with a single port 18, the lower end thereof being preferably tapered as indicated at 19. The said port is preferably so positioned that its lower end is in close proximity to the cam groove or track 20, within which is positioned a cam roller 21 upon the end of the wrist pin 6. The construction and arrangement of parts is such that upon imparting reciprocating movement to the piston 5, the cam roller 21, traveling in the cam track 20, imparts rotative movement to the sleeve valve 11.

Viewing Fig. 2, it will be observed that the width of the sleeve valve opening 18 is such that the exhaust port is wholly closed before the intake port is opened. Preferably the cylinder is so constructed and arranged that the intake and exhaust ports are spaced apart thirty degrees in one direction and 210 degrees in the opposite direction, the width of the sleeve valve port 18 being also preferably equal to thirty degrees of the periphery of the cylinder, and the length thereof being preferably equal to the full piston stroke.

In Fig. 3 I have represented a four cyl-

inder engine constructed in accordance with my invention, the cylinders being respectively indicated at A, B, C and D. The sleeve valve of cylinder A is represented as in firing position, that of the cylinder B as in exhaust position, that of the cylinder D as in intake position, and that of the cylinder C as in compression position.

As indicated most clearly in Fig. 4, the cam track 20 is so constructed that differential movements are imparted to the sleeve valve. In said figure, I have represented the cam track 20 as having four portions which I have respectively indicated as 22, 23, 24 and 25, and which are respectively intended to impart movement to said sleeve valve during the induction stroke, the compression stroke, the firing or ignition stroke, and the exhaust stroke.

At the commencement of the induction stroke the opening 18 in the sleeve valve coincides with the thirty degree solid wall between the exhaust and intake valve ports of the cylinder. As the piston 5 moves downward to commence the induction stroke, the sleeve valve is slowly turned so as to secure a slow initial opening of the intake port of the cylinder, and then during the continuation of the downward stroke of the piston a quick complete opening of said intake port is secured. By thus opening the intake valve by a slow initial action I secure substantially an atomizer action and obtain good vaporization without any tendency toward emulsion of the gasoline or other motive fluid. The parts are preferably so constructed that when the piston has moved downward one-third its stroke the entire sleeve valve port is in register with the intake port of the cylinder, making therefore available a valve space equaling the width of the sleeve port multiplied by one-third the piston stroke. On the second third of the stroke the sleeve valve port registers with the second half of the intake valve opening, so that when the piston is two-thirds down on the said induction stroke the available valve space equals two-thirds the piston stroke multiplied by the width of the sleeve port. On the last third of the said piston stroke the valve sleeve port gradually registers with the solid part of the cylinder wall. At the bottom of the said stroke the port is wholly closed, the available area of the sleeve valve port thus gradually decreasing to zero. During the compression and the explosion or firing strokes the sleeve valve port continues to register with the solid wall. As the piston commences to move upwardly upon the exhaust stroke the sleeve valve port commences to register with the first half of the exhaust valve port so that when the piston has moved up one-third its stroke the available valve space equals two-thirds the piston stroke multiplied by the sleeve valve

port width. During the second third of the exhaust stroke the sleeve valve port registers with the second half of the exhaust port, so that when the piston is two-thirds up on its exhaust stroke the available valve space equals one-third the piston stroke multiplied by the sleeve valve port width. During the last third of the piston stroke the sleeve port gradually registers with the thirty degree solid cylinder wall separating the intake and exhaust ports, thus closing the valve port.

The cam tracks 22, 23, 24 and 25 are so shaped as to effect the operation herein set forth. The inclination of the cam groove 24 for the explosion stroke is sharp at the commencement thereof, in order to take or relieve the shock of the parts incident to the movement of the sleeve valve. It will be noted that the curve of the cam track 25 is substantially flat at its commencement, so that the exhaust port will be quickly opened.

An important feature of the invention resides in the large port areas. As heretofore pointed out, the intake port has a length substantially equaling two-thirds the piston stroke, and the exhaust port has a length substantially equaling the full piston stroke. The port in the sleeve valve is preferably substantially thirty degrees in width, and it is preferably of the full length of the piston stroke.

Inasmuch as the lower right-hand corner portion of the sleeve valve port 18 (viewing Fig. 4) would be unused were said port rectangular, I preferably form said port with a tapering lower end, as there shown. I am thus enabled to bring the available area of said port into close proximity to the cam track 20, and thereby to shorten the height of the sleeve valve 11.

I have heretofore referred to the intake and exhaust ports as of preferably a width equaling sixty degrees of the periphery of the cylinder. The construction and operation of the parts are such that a portion of each of these ports is not uncovered by the port 18 of the sleeve valve into the rotative movement of the latter. The uncovered portions of said intake and exhaust ports (assuming that the sleeve valve is rotated at a constant speed) I have indicated at 26 and 27 in Fig. 5, the uncovered portion of the former equaling substantially one eighth and that of the latter equaling substantially one third of the entire area of said ports. Inasmuch, however, as the sleeve valve herein shown is rotated at differential speeds, the unused portion of said ports 9, 10 more nearly approximates the construction shown at 26', 27' in Fig. 6, wherein, however, I have not attempted accurately to plot the precise curve.

Inasmuch as the described portions of said ports are not used, I preferably replace

the same with solid portions of the cylinder, thus strengthening the latter and decreasing the pocket areas of the ports to that extent.

Preferably the cylinders shown in Fig. 3 are so constructed and arranged that the sleeve valves of the first and third turn in one direction and the sleeve valves of the second and fourth turn in the opposite direction. This may be effected by connecting 10 the wrist pins of said cylinders alternately at opposite sides of the said cylinders. As shown, however, the sleeve valves all rotate in the same direction.

I have herein illustrated the wrist pins as 15 constituting the means for rotating the sleeve valves, but if desired any other suitable means may be employed, my invention not being limited to the employment of the wrist pin for this purpose.

20 The internal combustion engine herein disclosed is of simple construction, necessitating the use of but a single valve, and the latter is preferably operated directly by the wrist pin of the piston.

25 Having thus described one illustrative embodiment of my invention, I desire it to be understood that although specific terms are employed, they are used in a generic and descriptive sense and not for purposes 30 of limitation, the scope of the invention being set forth in the following claims.

I claim:

35 1. An internal combustion engine comprising, in combination, a cylinder having intake and exhaust ports, a piston reciprocable in said cylinder, a sleeve valve mounted to turn with respect to said cylinder and having a port therein provided with a tapered lower end, and co-acting means upon 40 said valve and piston to turn the former.

45 2. An internal combustion engine comprising, in combination, a cylinder having intake and exhaust ports, a piston reciprocable in said cylinder and provided with a wrist pin and a piston rod connected thereto, a sleeve valve mounted concentrically with respect to said cylinder and having a port therein and a cam track, said wrist pin having an extension positioned in said cam track.

50 3. An internal combustion engine comprising, in combination, a cylinder having a single intake and a single exhaust port of substantially equal width, a piston reciprocable in said cylinder, a sleeve valve mounted concentrically and arranged to turn with respect to said cylinder and having a port therein of a width substantially one-half either the intake or the exhaust port, and means to rotate said sleeve valve.

55 60 4. An internal combustion engine comprising, in combination, a cylinder, a piston reciprocable therein, said cylinder having an intake port of a length substantially equaling two-thirds the piston stroke and an exhaust port substantially equaling the

full piston stroke, a sleeve valve mounted concentrically and adapted to turn with respect to said cylinder and having a port therein of substantially the length of the full piston stroke, and means to rotate said 70 sleeve valve.

5. An internal combustion engine comprising, in combination, a cylinder, a piston reciprocable therein, said cylinder having intake and exhaust ports of substantially equal width, the intake port being of a length substantially equaling two-thirds the piston stroke and the exhaust port being of a length substantially equaling the full piston stroke, a sleeve valve mounted 75 concentrically and adapted to turn with respect to said cylinder and having a port therein of a width substantially one-half the width of the intake or the exhaust ports and of a length substantially equaling the full piston 80 stroke, and means to rotate said sleeve valve.

6. An internal combustion engine comprising, in combination, a cylinder, a piston reciprocable therein, said cylinder having intake and exhaust ports, the exhaust port 90 being of a length substantially equaling the full piston stroke, a sleeve valve mounted concentrically and adapted to turn with respect to said cylinder and having a port therein of substantially the length of the 95 full piston stroke, and means to rotate said sleeve valve.

7. An internal combustion engine comprising, in combination, a cylinder having intake and exhaust ports, a piston reciprocable in said cylinder, a sleeve valve mounted to turn with respect to said cylinder and having a port therein, and means to rotate 100 said sleeve valve, said intake and exhaust ports each having one lateral wall thereof 105 inclined at its lower end.

8. An internal combustion engine comprising, in combination, a cylinder having a recess and intake and exhaust ports, a piston reciprocable in said cylinder, a straight 110 sleeve valve mounted in said cylinder recess, and having a port and a cam track therein, ball bearings at the ends of said sleeve to reduce the friction thereof, and means projecting from said piston into said track for 115 imparting rotative movement to said sleeve with respect to said cylinder.

9. An internal combustion engine comprising, in combination, a cylinder having a recess and intake and exhaust ports, a piston 120 reciprocable in said cylinder, a straight sleeve valve mounted in said cylinder recess and having a port and a cam track therein, and means projecting from said piston into said track for imparting rotative movement 125 to said sleeve with respect to said cylinder.

10. An internal combustion engine comprising, in combination, a cylinder, a piston reciprocable therein, said cylinder having intake and exhaust ports of substantially 130

equal width, the exhaust port being of a length substantially equaling the full piston stroke, a sleeve valve mounted concentrically and adapted to turn with respect to said cylinder and having a port therein of a width substantially one-half the width of the intake or the exhaust ports and of a length substantially equaling the full stroke, and means to rotate said sleeve valve.

In testimony whereof, I have signed my name to this specification, in the presence of two subscribing witnesses.
